UNITED STATES PATENT OFFICE.

PERRY WILLIAM FISHER, OF YREKA, CALIFORNIA.

FIRE LOCATOR.

Application filed January 25, 1924. Serial No. 688,541.

This invention relates to instruments for predetermining the location of forest fires.

Heretofore it has been necessary in locating forest fires to take an angular or azimuth reading from two stations. The stations must be in constant communication for comparison and platting before an accurate determination of the location of the fire is had.

10 It is an object of my invention to provide a device for determining the position of forest fires either in the day time or at night without necessitating telephonic communication between several stations and 15 the usual platting before the position of the fire has been approximately determined.

A further object of the invention is the provision of a device adapted to be operated in conjunction with a map of the surrounding country for determining the position of the fire on the map and thus providing for a rapid and accurate computation of the location of the fire solely from a single station.

25 This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the 35 appended claims.

In the drawings:

Figure 1 is a side view of an instrument for locating fires.

Figure 2 is a plan view of the same.

40 Referring more particularly to the drawings, 1 designates a base plate or table upon which is placed a map 2 of the surrounding region of the country in which the "look-out" station is located. A margin 3 is provided, the outer periphery of which is divided into 360 degrees, with numerals designating every 10 degrees of the circle. A pintle 4 is provided at the center of the table or base member 1 and upon which is 45 mounted a post 5. The upper end of the post is bifurcated to receive the middle portion of a telescope 6. The legs of the bifurcated portion of the post is provided with bearings adapted to receive the trunnions 7 which are adapted to support the telescope in the vertical plane and permit

tilting of the telescope in opposite direction.

An arcuately shaped rack 8 has its opposite ends connected, as shown at 9 and 10, to the under portion of the telescope 60 so that the teeth 11 of the rack will engage the teeth of gear wheel 12 mounted on a shaft 13. Bearings are provided in the post 5 for carrying the shaft 13.

A gear wheel 14 is rigidly connected with 65 the shaft and is located between the side members 15 which form part of the lower end of the post 5, the wheel 14 being rotatable between said side members.

A horizontal rack 16 is slidable within 70 a horizontal guide bar 17 and is adapted to mesh with the gear 14 so that when said gear is rotated the rack 16 will be moved diametrically of the circular map 2. The outer end of the guide bar 17 is supported 75 by a diagonally disposed brace bar 18 which has its upper end connected to the post 5. The inner end of the guide bar 17 is rigidly connected with the lower end of the post which is adjacent to the table 1. The inner 80 end of the rack 16 is provided with a clamp 19 adapted to carry a pointer 20 which is movable over the face of the map. A hand wheel 21 is rigidly connected with the shaft 13 for manually rotating the shaft. 85

The circular cardboard or paper upon which the map is laid out is fixed to the table 1 and the inner circle 22 is drawn to form the marginal border 3 in which the numbers are located adjacent the calibrations at the outer periphery of the map for designating the various degrees of such circular periphery. The surrounding country is diagrammatically platted on the map in such a manner that the rotary movement 95 of the post 5 carrying the telescope 6, rack 16 and the pointer 20 around the various portions of the map so that the map, when properly located in a "look-out" station will be positioned to show an accurate location 100 of the various parts through the movement of the telescope from the horizontal and the radial movement of the telescope through the post 5.

When a fire either in the day or night 105 is observed the telescope 6 is not only revolved but is tilted from the horizontal until the hair-line of the telescope is disclosed directly in the path of the fire. By observing the position of the pointer 20 on 110 the map, an exact location of the fire is had. This is due to the fact that the rack

16 cooperates with the rack 8. When the wheel 21 is revolved to properly position the telescope 6 after sighting a fire, the rack 16 is moved radially of the map 2 in proportion to the horizontal oscillation of the telescope 6 so that the pointer will fall upon the place which designates the exact position on the map and therefore predetermines the exact position of the fire from 10 the "look-out" station by a single observation. The movement of the telescope 6 in a horizontal plane is had through grasping the rod 18 and moving it for revolving the post 5 and locating the angular position of the telescope 6.

It will be seen that by my device fires may be located as accurately at night as may be done during the day and that it is not necessary for a "look-out" to be familiar 20 with the surrounding country to determine the location of fires since the position of the telescope and the pointer gives the exact location of the fire and since the determination of the position of the fire is made by 25 a "look-out" independently of other "look-outs" in other stations there will be no dispute between the various "look-outs" as to the exact location of a fire.

The horizontal guide bar 17 and the brace 30 bar 18 together form a bracket projecting laterally from the post whereby the post and telescope 6 may be revolved by the angular rotation of said bracket for directing the telescope for alinement with a forest fire. The angular movement of the bracket locates the pointer 20 on a line passing 35 through a calibration at the periphery of the map which is described as degrees. The selected line as designated by a certain degree passes through the objective in the field or in other words through the fire. The oscillation of the telescope above or below the horizontal causes a further adjustment of the pointer radially of the line for an accurate determination of the position of the fire on the map.

The construction of the map must be such that the cooperative movements of the oscillating and rotating telescope will properly 50 position the pointer 20 upon the location on the map which will indicate the position of the fire in the field and whereby an unskilled "look-out" will be able to readily determine such position.

55 It is understood that the rotatable member 5 at the "look-out" post is at the center of the territory which is under the direct supervision of the "look-out" at that point so that the revolution of the telescope will

bring all points of the territory under observation. 60

The post 5 is provided with a longitudinal slot through which is movable the lower portion of the arcuately shaped rack 8 and the horizontal rack 16. The gears 12 and 65 14 are likewise located within the slot of the post.

What I claim is:

1. In a device of the character described, a horizontal base, a circular map mounted 70 thereon, a post mounted on the base for rotation about a vertical axis at the center of the map, a telescope pivotally mounted at the upper end of the post for rotation about a horizontal axis, an arcuately shaped 75 rack connected to the telescope, and depending from the same, a shaft mounted for rotation in the post, a gear on the shaft and engageable with the arcuately shaped rack, a second gear rigidly connected with the 80 shaft, a bracket extending laterally from the post, a rack provided with a pointer movable over the map, said rack being 85 slideable in the bracket and in mesh with the second mentioned gear whereby rotation of the shaft will cause tilting of the telescope from the horizontal, and reciprocation of the rack radially of the map for positioning the pointer on the map.

2. In a device of the character described, a horizontal base, a circular map mounted thereon and representative of a territory at the center of which the map is located, a post mounted on the base for rotation about a vertical axis at the center of the map, a telescope pivotally mounted at the upper end of the post for rotation about a horizontal axis, and an arcuately shaped rack connected to the telescope and depending from the same, said post being provided with a longitudinal slot, a shaft mounted transversely of the slot in the post, a gear on the shaft located within the slot and engageable with the arcuately shaped rack, the lower end of the rack being located within the slot, a second gear rigidly connected with the shaft and located within the slot, a bracket extending laterally from the post, a horizontal rack provided with a pointer 95 movable over the map, said rack being slideable in the bracket and through the slot in the post and in mesh with the second mentioned gear, whereby rotation of the shaft 100 will cause tilting of the telescope from the horizontal and the simultaneous reciprocation of the horizontal rack radially of the map for positioning the pointer on the map. 105
